US00D859058S

(12) **United States Design Patent** (10) Patent No.: **US D859,058 S**
(45) Date of Patent: ** *Sep. 10, 2019

(54) **COOKING APPARATUS**

- (71) Applicant: **Tristar Products, Inc.**, Fairfield, NJ (US)
- (72) Inventors: **Keith Mirchandani**, Fairfield, NJ (US); **Paul McGrath**, Flanders, NJ (US); **James Mitrik**, Long Pond, PA (US); **Alejandro G. Lozano**, Guttenberg, NJ (US)
- (73) Assignee: **Tristar Products, Inc.**, Fairfield, NJ (US)
- (*) Notice: This patent is subject to a terminal disclaimer.
- (**) Term: **15 Years**
- (21) Appl. No.: **29/596,315**
- (22) Filed: **Mar. 7, 2017**

(57) **CLAIM**

The ornamental design for a cooking apparatus, as shown and described.

DESCRIPTION

FIG. 1 is a top perspective view of a first embodiment of a cooking apparatus in accordance with the subject disclosure. FIG. 2 is a top view of the cooking apparatus of FIG. 1. FIG. 3 is a bottom view of the cooking apparatus of FIG. 1. FIG. 4 is a front view of the cooking apparatus of FIG. 1. FIG. 5 is a rear view of the cooking apparatus of FIG. 1. FIG. 6 is another top perspective view of the cooking apparatus of FIG. 1. FIG. 7 is a bottom perspective view of the cooking apparatus of FIG. 1. FIG. 8 is a right side view of the cooking apparatus of FIG. 1. FIG. 9 is a left side view of the cooking apparatus of FIG. 1; and, FIG. 10 is a top perspective view of a second embodiment of the cooking apparatus of FIG. 1 indicating surface shading for metal.
